UNITED STATES PATENT OFFICE.

BENJAMIN F. BEE, OF HARWICH, MASSACHUSETTS.

CENTRIFUGAL PUMP.

SPECIFICATION forming part of Letters Patent No. 478,307, dated July 5, 1892.

Application filed August 22, 1891. Serial No. 403,386. (No model.)

To all whom it may concern:

Be it known that I, BENJAMIN F. BEE, a citizen of the United States, residing at Harwich, in the county of Barnstable and State of Massachusetts, have invented a new and useful Centrifugal Pump, of which the following is a specification.

This invention relates to centrifugal pumps; and it has for its objects to provide a pump of cheap and simple construction and adapted to have increased power for elevating or discharging received water, and which by its special construction prevents the formation of eddies, which generally occur in devices of this character, thus adding greatly to the efficiency of the apparatus.

Other objects and advantages of the invention will appear in the following description and the novel features thereof will be particularly pointed out in the claims.

Referring to the drawings, Figure 1 is a perspective view of a centrifugal pump constructed in accordance with my invention. Fig. 2 is a transverse section. Fig. 3 is a vertical transverse section. Fig. 4 is a detail in perspective of the water-wheel.

Like numerals of reference indicate like parts in all the figures of the drawings.

1 indicates the base of the casing; and the same is provided near its center with a circular water-receiving opening 2, and located upon the base is a vertical flange 3, spirally disposed around the opening and eccentric with relation thereto, and at its inner extremity abruptly disposed to combine with the outer extremity to form an outlet-spout 4. By reason of the spiral disposition, and consequent eccentricity of the wall, the space between said wall and the edge of the opening is gradually decreased from the outlet to the inner end of the wall, and thus allows the water greater impulse under the centrifugal impulsion from the means to be described. At intervals there is secured to the base near the edge of the opening vertical deflectors or blades 5, which in transverse section are curved to agree with the opening in the base and receive and deflect the discharged water. The wall has bolted thereto, as at 6, a cover 7, and the same is provided with a central countersunk recess 8, having a central opening 9.

To the under side of the base is secured an inlet-box 10, having a flared inlet-spout 11, said box being directly under the opening 2 of the base and adapted to receive and conduct the water within the casing under the action of the wheel within the casing, which subsequently discharges the same under force.

Uprights 12 project from the base at diagonally-opposite corners, and the two are connected by a cross-bar 13, having a bearing 14, concentric with and vertically above the opening 9 in the countersunk recess 8 of the top 7, and also vertically above a bearing 15, formed in the box 10. In the bearings 14 and 15, and passing through the opening 9, is a vertical shaft 16, which near the bearing 14 carries a pulley 17, around which passes a belt to any suitable motive power, which revolves the wheel located within the casing and carried by said shaft.

Fixed upon the shaft 16, beneath the cap 7, is a disk 18, provided with a central hub 19, to which and the disk there is bolted a pair of diametrically - opposite depending blades or floats 20, which blades are of such diameter as to extend to the outer edge of the disk and are provided with flanged ends 21, slightly overlapping the circular opening 8 of the base, and at their outer edges come in close proximity to the vertical curved deflecting-blades 5.

If desired, three blades may be employed; but I prefer two, as by experience I have found a much better result is obtained. The water is drawn from the source of supply through the inlet into the receiving-box 10 and is delivered therefrom through the opening in the bottom of the casing to the revolving disk and blades or floats, which in their rotary motion catch the water and throw the same against the vertical deflecting-plates, which receive the same and direct it around the scroll-casing and give it impulse in its proper course toward the delivery-spout 4, previously referred to.

The deflecting-plates additionally serve to prevent the formation of eddies and the consequent impediment to the free expulsion of the water by the wheel.

I prefer to construct the blades 20 of L shape, or with their lower edges laterally bent to form the flanges 21, which are at

right angles to the bodies of the blades, and these flanges have their side edges opposite those portions above the opening 2 depressed or inclined, as at 22, so as to move easily and readily grasp the water received therebeneath and greatly facilitate its discharge, the water being given a revolving or whirling motion by the revolving floats or blades and is sent tangentially therefrom under a greater impetus than is generally the case.

Having described my invention, what I claim is—

1. In a centrifugal pump, the combination, with the case having the vertical inlet-opening eccentrically related with the wall of the case, of the shaft passing through the case and opening, a disk on the shaft, and blades depending from the disk over the opening and having laterally-bent flanges at their lower edges overlapping the edge of said vertical opening and traveling horizontally thereover, substantially as specified.
2. In a centrifugal pump, the combination, with the scroll or spiral case having the vertical inlet-opening eccentrically related with the wall of the case, of the shaft passing through the case and opening, a flat disk on the shaft above said opening, and straight blades depending from the disk over the opening and having laterally-bent flanges at their lower edges, said flanges overlapping and extending beyond the edge of the opening and traveling horizontally thereover and having those portions above the opening downwardly inclined or bent, substantially as specified.
3. In a centrifugal pump, the combination, with the casing comprising the base, having the circular inlet-opening, and the spiral vertical wall eccentrically disposed with relation to the opening and terminating at one side in a discharge-spout, and a cover for the case, having an opening, of vertical curved deflect-

ing-plates secured to the base within the casing near to and concentric with the edges of the opening, a shaft passing through the case and opening, and a disk mounted on the shaft and provided with depending blades traveling within said plate and over the edges of said inlet-opening, substantially as specified.

4. In a pump of the class described, the combination, with the casing comprising the base having the inlet-opening, the vertical spiral wall located adjacent to and eccentric with relation to the opening and having the discharge, the cover having the countersunk recess above the opening and provided with an opening, the receiving-box having the inlet located below the opening in the base, and the series of vertical transversely-curved deflecting-plates mounted on the base adjacent to and concentric with the opening and within the casing, of the opposite standards extending from the base, the transverse connecting-bar having a bearing vertically opposite the openings in the base and cover, and a bearing formed in the bottom of the discharge-box, the vertical shaft mounted in the bearings, the pulley on the shaft above the case, the disk upon the shaft within the base, and the depending L-shaped blades secured to the disk and having their horizontal wing portions traveling over and overlapping the edge of the opening in the base and having the said horizontal portions thereof immediately above the opening downwardly bent, substantially as specified.

In testimony that I claim the foregoing as my own I have hereto affixed my signature in presence of two witnesses.

BENJAMIN F. BEE.
